CLAIM

The ornamental design for a display screen or portion thereof with graphical user interface for a sterilizer, as shown and described.

DESCRIPTION

FIG. 1 is a front view of a first image of the display screen or portion thereof with graphical user interface for a sterilizer showing my new design;

FIG. 2 is a front view of the second image thereof;

FIG. 3 is a front view of the third image thereof;

FIG. 4 is a front view of the fourth image thereof;

FIG. 5 is a front view of the fifth image thereof;

FIG. 6 is a front view of the sixth image thereof;

FIG. 7 is a front view of the seventh image thereof;

FIG. 8 is a front view of the eighth image thereof;

FIG. 9 is a front view of the ninth image thereof;

FIG. 10 is a front view of the tenth image thereof; and,

FIG. 11 is a front view of the eleventh image thereof.

The outermost broken lines show a display screen or portion thereof and form no part of the claimed design. The remaining broken lines show portions of the graphical user interface and form no part of the claimed design.

The subject matter in this patent includes a process or period in which an image changes into another image. This process or period forms no part of the claimed design.
